UNITED STATES PATENT OFFICE.

FRANCIS M. RITES, OF PITTSBURG, PENNSYLVANIA.

STEAM-ENGINE GOVERNOR.

SPECIFICATION forming part of Letters Patent No. 355,717, dated January 11, 1887.

Application filed September 1, 1886. Serial No. 212,351. (No model.)

To all whom it may concern:

Be it known that I, FRANCIS M. RITES, residing at Pittsburg, in the county of Allegheny and State of Pennsylvania, a citizen of the United States, have invented or discovered certain new and useful Improvements in Steam-Engine Governors, of which improvements the following is a specification.

My invention relates to automatic cut - off governors of the class which are mounted upon the main or crank shaft of the engine and effect regulation by variation of the position of an adjustable eccentric actuating a valve which governs the supply of steam to the cylinder; and its object is to provide a governor specially adapted to engines having their distribution-valves reciprocating in substantially vertical planes, in the employment of which, under a simplified and economical construction, the gravity of the eccentric and of the reciprocating parts shall be effectively counterbalanced and the weight of the eccentric reduced to the minimum compatible with required strength.

To this end my invention, generally stated, consists in the combination of an adjustable eccentric or crank-pin pivoted upon a crank-shaft, and coupled to a valve reciprocating in a substantially vertical plane, and a governor-weight pivoted upon the crank-shaft and coupled to the eccentric in such manner as to move in opposite direction thereto.

The improvements claimed are hereinafter fully set forth.

In previous constructions of the class to which my invention relates the gravity of the reciprocating parts has been balanced by provision for the exertion of an upwardly-acting force, and it has ordinarily been necessary to employ two governor - weights coupled together and pivoted at opposite points to a supporting member on the shaft, so as to balance each other as well as to counterbalance the eccentric by a corresponding weight.

I am further aware that governors having but a single weight, the gravity of which is counterbalanced by that of the eccentric, have been heretofore known and used; but such require a comparatively heavy eccentric and are incapable of effective operation with a vertically-reciprocating valve without the provision of a special balancing device for grav-

ity of the reciprocating parts. Under my invention such balance is effected by the gravity of the single weight, and the eccentric, being freed from balancing function, may be made as light as its strength will permit, or a single crank-pin may be employed in its stead.

In the accompanying drawings, Figure 1 is a vertical transverse section through a steam-engine, taken at the center of the valve-chest, showing a face view of a governor embodying my invention; Fig. 2, a side view in elevation of the governor; Fig. 3, a face view of the crank-arm, illustrating more fully the positions of the pivots of the eccentric and weight; and Fig. 4, a similar view of the same with the weight and spring attached.

The engine in which my invention is herein shown as applied is of the vertical single-acting type, having its cylinders 1 secured upon the top of a crank case or box, 3, provided with proper end bearings for a crank-shaft, 5, having double cranks 2, to the pins 4 of which the pistons of the cylinders 1 are coupled by connecting-rods. The admission and exhaust of steam to and from the cylinder 1 is effected by a distribution-valve, 7, composed of an upper piston, 8, and a lower piston, 9, fixed upon a valve-stem, 10, which is adapted to reciprocate in a sleeve or bushing, 11, provided with proper steam and exhaust ports, and fixed in a valve-chest, 12, located between the cylinders 1, and slightly inclined relatively thereto, such construction being one of the numerous types of vertical engines to which my improvements are desirably applicable.

In the practice of my invention the distribution-valve 7 is reciprocated by an eccentric, 13, the strap 19 of which is secured to one end of an eccentric-rod, 20, whose opposite end is coupled by a pin, 21, to the valve 7, the throw of said eccentric being varied as required in the operation of the engine by adjustment of its position relatively to the crank-line, in order to vary the travel of the valve, and consequently the degree of expansion or point of cut off, as presently to be described. A crank-pin coupled to the lower end of the eccentric-rod would perform as an equivalent 95 function of the eccentric.

The eccentric 13 is made as light as may suffice to afford sufficient strength, being, as shown, a simple ring formed in halves or sec-

tions, bolted together for convenience of application, and having an arm or lug, 15, on one of its sections, which is pivoted by a pin, 16, to the arm of one of the cranks 2 of the crank-shaft 5.

It will be seen that by movement of the eccentric in one or the other direction about the axis of its pivot 16 its throw, and consequently the degree of traverse which it imparts to the valve 7, is increased or diminished, as the case may be, such movement being imparted to the eccentric by the tension of a spring, 14, or the centrifugal force of a governor-weight, 26, as either may preponderate under varying conditions of pressure or resistance, or both.

A single governor-weight, 26, is pivoted by a pin, 17, to an extension of the crank-arm 6, and is coupled directly by a link, 18, to the lug 15, which receives the pivot 16 of the eccentric, the relation of the pivots 16 and 17 of the eccentric and weight to the link 18 being such that the eccentric and weight are compelled to move in opposite directions, and the gravity of the reciprocating parts—to wit, the eccentric-rod and valve—which are connected to the eccentric is exerted in opposition to that of the governor-weight—that is to say, downward or outward movement of the weight induces corresponding upward movement of the eccentric and reciprocating parts, and vice versa. The direct connection of the governor-weight and eccentric by the single link 18 enables the gravity of the governor-weight to be made available as a counter-balance to that of the reciprocating parts of the valve-motion in any and all positions assumed by the weight under the influence of centrifugal force.

In the construction shown the eccentric and governor-weight are pivoted to the crank-arm on opposite sides of the shaft; but such location is not an essential one, as both might be pivoted on the same side, and by suitable connections to an intermediate sleeve the balancing action of the governor-weight and the reciprocating parts could be equivalently provided for.

The rule which governs the location of the pivots of the eccentric and of the governor-weight, respectively, is that the angle formed by a line drawn from the center of the shaft through the center of the eccentric pivot to the line of valve travel with a vertical line shall be equal to the angle formed by a line drawn from the center of the weight-pivot to the center of gravity of the weight with the line of valve travel—that is to say, when a line drawn through the center of the shaft and center of the eccentric pivot coincides with the line of valve travel, the center of gravity

of the weight shall be in line vertically with the center of the weight-pivot.

The outward movement of the weight upon its pivot 17, under the influence of centrifugal force, by which the throw of the eccentric is reduced, is opposed by the tension of a helical spring, 14, by which the throw of the eccentric and travel of the valve are increased in accordance with increase of load or diminution of pressure, or both, as from time to time required. The spring 14 bears at one end against an abutment, 22, on the crank-arm, and at the other against a stop, 23, on a pin, 24, which passes freely through an opening in the crank-arm, and is coupled to the weight 26. The tension of the spring 14 may be varied by the adjustment of a nut, 25, engaging a screw-thread on the pin 24, and forming an abutment for the stop 23.

My invention, in addition to simplifying and reducing the cost of an automatic cut-off mechanism, possesses the further advantage of presenting the same in such form as to be readily adaptable to operation within the contracted compass of a closed crank-case. The substantial reduction of weight of the eccentric and the permissible substitution of a light crank-pin renders a counter-balance unnecessary, and the gravity of the reciprocating parts is fully balanced in all positions of the valve by that of the governor-weight.

I claim as my invention and desire to secure by Letters Patent—

1. The combination of a distribution-valve adapted to reciprocate in a substantially vertical plane, an eccentric or crank-pin pivoted upon a crank-shaft and coupled to the distribution-valve, and a single governor-weight pivoted upon the crank-shaft and coupled to the eccentric, the pivots of the eccentric and of the governor-weight being relatively located, as described, so that the gravity of the reciprocating parts of the valve-motion shall be counterbalanced by that of the governor-weight, substantially as set forth.

2. The combination of a crank-arm, an eccentric pivoted thereto on one side of the axis of the crank-shaft, a governor-weight pivoted thereto on the opposite side of the axis of the crank-shaft, a direct link-connection coupling the governor-weight and eccentric on the side of the crank-shaft farthest from the free end of the weight, and a spring bearing against the crank-arm and against the governor-weight, substantially as set forth.

In testimony whereof I have hereunto set my hand.

FRANCIS M. RITES.
